UNITED STATES PATENT OFFICE.

LEE ROY APPLEGATE, OF SEATTLE, WASHINGTON, ASSIGNOR TO UTILITY MANUFACTURING COMPANY, OF SEATTLE, WASHINGTON, A CORPORATION OF WASHINGTON.

PUMP.

1,150,803.

Specification of Letters Patent. Patented Aug. 17, 1915.

Application filed May 9, 1914. Serial No. 837,963.

To all whom it may concern:

Be it known that I, LEE ROY APPLEGATE, a citizen of the United States, and resident of Seattle, King county, Washington, have invented certain new and useful Improvements in Pumps, of which the following is a specification.

My invention relates to pumps and comprises certain improvements in pumps of that type in which multiple cylinders are employed and which are driven by a power connection.

The object of my invention is to produce a pump of simple construction and design which will be reliable in its action and of a low cost, such as will enable it to be used for many purposes where an expensive pump would not be suitable.

The features of which my invention consists will be defined in the claims.

In the accompanying drawings I have shown my invention embodied in the form which is now preferred by me.

Figure 1 is a front elevation of the pump showing one end thereof in vertical section. Fig. 2 is an end elevation showing the base and a portion of one cylinder in section. Fig. 3 shows one of the valves in perspective. Fig. 4 is a central transverse sectional elevation, the cranks and pistons being omitted. Fig. 5 is a plan view of the base, with portions of the valve chamber covering plates removed, and with the cylinders in place. Fig. 6 is a bottom plan view of the plate which engages the upper ends of the cylinders.

The base 1 contains therein a series of transverse channels 10, the number of which corresponds with the number of cylinders used in the pump. Each of these channels has an upwardly extending opening 11 designed to communicate with the cylinder which is employed in connection therewith. The upper surface of the casing surrounding these openings is slightly recessed to form a ledge 9 which receives and supports the lower end of its cylinder 3. The cylinders are preferably made as plain tubular shells.

At each side of the casing channels are formed connecting all of the transverse channels 10. The channel 18 at one side of the casing constitutes an inlet header from which the water is supplied to all the trans-

verse channels 10. The channel 13 which is

at the opposite side of the base communicates with the opposite ends of all the channels 10, and constitutes the discharge header. Between the connection with the cylinder and the inlet header each transverse channel 10 is provided with a chamber 12 which extends upwardly to the upper surface of the base and constitutes a valve chamber. In this chamber is placed a valve 2 which is adapted to close the port 19 which connects the channel 10 with the inlet header 18. In the wall of the casing lying between the valve chamber 12 and the inlet header 18 is formed a slot of T-shape, extending from the upper surface of the casing downward to a point close to the port 19. This slot is made with the stem of the T communicating with the valve chamber 12. The valve which is used is shown in perspective in Fig. 3. This consists of a plate 2, of a size and shape to satisfactorily close the port 19, provided at its upper edge with a curved or elbow-shaped arm 20, having at its end a transverse bar 21, which arm and head are adapted to enter the T-shaped slot 22. At the opposite end of the transverse channel 10 the port 14 which communicates with the discharge header 13 is closed by a valve of the same construction and mounting. An inlet and outlet valve of this character is provided for each of the transverse channels 10.

The inlet header 18 and the valve chambers 12 are closed at their upper side by a plate 15 which is bolted down thereon, and the outlet header 13 is closed in a similar manner by a plate 16. Plate 16 is provided with an opening for the reception of the discharge pipe 8.

A standard 5 is secured at each end of the base, and extends upwardly, providing bearing 61 for the crank shaft 6. This standard has a cross bar 50 located at a point approximating in level to that of the upper ends of cylinders 3, preferably being slightly lower than the ends of the cylinders. A plate 4, shown in bottom plan view in Fig. 6, is provided with openings 40 having recesses 41 in the lower surface of the plate adapted to receive the upper ends of the cylinders 3. This plate has ends 42 which project between the side bars of the standard 5 and over the cross bar 50, to which the plate is bolted so as to be drawn strongly down upon the ends of the cylinders.

Where several cylinders are used, as shown

in the drawings, central holding-down bars 44 should be employed, these passing through the plate and being anchored in the base 1. These bolts may also be employed to hold 5 down a short standard 52, which contains a central bearing 62 for the crank shaft.

The crank shaft 6 is provided with a series of cranks 60, one for each cylinder, upon the bearings of which are journaled 10 the connecting rods 31, the other ends of these rods being pivoted in the pistons 30. This crank shaft may also be provided with a shell 63, or any other suitable means for turning the same.

15 The construction above described is one which is very simple and cheap to make, and one which is easily maintained in good working condition. The type of valve employed is one which provides a large opening with a small movement, is cheap to make, and will close quickly.

What I claim as my invention and desire to patent is:

1. A multiple cylinder pump having a 25 base provided with a series of shallow, cylinder-seating recesses arranged in a central row, a series of water conduits extending transversely of said row of cylinder seating recesses, one below and communicating with 30 each cylinder seating recess, a valve controlling each end of each of said transverse conduits, the upper walls of said conduits having openings over and giving access to each of said valves, said base having header channels connecting the ends of said transverse conduits and provided with means for connecting with supply and discharge pipes, and plates for closing the openings into said channels.

40 2. A multiple cylinder pump comprising a base having supply and discharge ports therein and an alined row of cylinder seating recesses in its upper surface, each communicating with a separate port, a series of 45 plain tubular cylinders lacking end closures, each seating in one of the said recesses, a plate having a corresponding series of alined cylinder seating recesses placed upon the upper end of the cylinders and having holes therethrough communicating with the cylinder bores, and tension bolts connecting said plate with the base.

3. A multiple cylinder pump comprising a base having supply and discharge ports 55 therein and an alined row of cylinder seating recesses in its upper surface, each communicating with a separate port, a series of plain tubular cylinders lacking end closures,

each seating in one of the said recesses, a plate having a corresponding series of alined cylinder seating recesses placed upon the upper end of the cylinders and having holes therethrough communicating with the cylinder bores, a frame standard at each end of the row of cylinders extending upward from the base, a crank shaft journaled in said standards, and means for bolting the plate which engages the upper ends of the cylinders down upon said standards, and tension bolts connecting said plate with the base intermediate its ends.

4. A multiple cylinder pump comprising a base having supply and discharge ports and controlling valves therein and having an alined row of cylinder seating recesses in its 75 upper face and openings connecting each of said cylinder seats with its respective ports in the base, a series of cylinders each consisting of a plain tubular shell fitted, each to its respective seat, a standard extending 80 upward from the base at each end of the row of cylinders and provided with a shaft bearing at its upper end and a ledge at a level corresponding to the upper ends of the cylinders, a plate having cylinder centering and holding means extending over the row of cylinders and having holes therein corresponding with the cylinder bores, the ends of said plate being clamped down upon the ledges of the end standards, tension bolts connecting the central portion of said plate with the base, and a shaft bearing member supported from the said plate and secured by said tension bolts.

5. A pump having a base provided with 95 a channel communicating with the pump cylinder and at each side of this connection having a valve chamber extending upwardly and opening at the upper surface of the base, one side wall of said chamber constituting a valve seat, said wall, above the port therethrough, having a T-shaped recess extending from the upper surface of the base downward with the base of the T opening into the valve chamber, and valves each 100 having an elbow-shaped central arm terminating in a transverse bar adapted to fit into the recess in the chamber wall, and plates closing the upper opening of said chamber.

In testimony whereof I have hereunto 110 affixed my signature this 1st day of May, 1914.

LEE ROY APPLEGATE.
